[57] CLAIM

The ornamental design for an insect trap, as shown.

DESCRIPTION

FIG. 1 is a top plan view of an insect trap embodying
my design;

FIG. 2 is a bottom plan view thereof;

FIG. 3 is a typical side view thereof with the openings
closed;

FIG. 4 is a typical side view with the openings open;

FIG. 5 is a vertical section taken along line 5—5 of FIG.
2; and

FIG. 6 is a vertical section taken along line 6—6 of FIG.
1.
